LIFTING JACK

Millard B. Lucker, St. Joseph, Mich., assignor to
Auto Specialties Manufacturing Company, St.
Joseph, Mich., a corporation of Michigan

Application October 5, 1935, Serial No. 43,752

11 Claims. (Cl. 254—106)

This invention relates to lifting jacks, and more particularly to jacks of the frictional grip type especially adapted for use with automotive vehicles and the like.

5 It is an object of the invention to produce a lifting jack of the friction grip type which provides a relatively large range of lifting movement; and to produce a jack in which the lifting member which engages the device to be raised 10 may be readily adjusted as to height and position to facilitate the operative engagement with such device.

A further object of the invention is to provide 15 means for insuring the necessary movements of the actuating clamp under all conditions of operation, and for insuring the invariable and rapid gripping action of the holding clamp whereby to prevent inadvertent release of the holding clamp and to facilitate even and controlled lowering 20 movement of the lifting member.

A still further object of the invention is to produce a jack having the above features of construction which may be readily produced and assembled, which is durable, and which is reliable 25 and efficient in operation.

Other objects and advantages of the invention will appear from the following specification when taken in connection with the accompanying drawing wherein like reference numerals refer to like 30 parts throughout.

In the drawing:

Figure 1 is an elevational view showing a lifting jack construction embodying the features of the invention.

35 Figure 2 is a partial longitudinal sectional view taken along the line 2—2 of Figure 3.

Figure 3 is a partial longitudinal sectional view taken along the line 3—3 of Figure 1.

Figure 4 is a transverse section along the line 40 4—4 of Figure 1.

Figure 5 is a view similar to Figure 2, but showing the parts with the jack operating lever in raised or actuated position.

Figure 6 is a detail perspective of the holding 45 clamp; and

Figure 7 is a detail perspective of the actuating clamp.

The embodiment of the invention shown in the drawing for purposes of illustration comprises a 50 base 10 having pinned or otherwise suitably fixed thereto an upstanding shaft or standard 11. The standard 11 carries the lifting casting 12 which is adapted for sliding movement therealong. The casting 12 has formed at its upper portion a plurality of contact notches 13 which are adapted

for engagement with the device to be lifted. In the drawing such device is illustrated as a portion 14 of the bumper of an automotive vehicle as the lifting jack of the present invention is particularly adapted for use in such connection. 5 However, it is to be understood that the jack may be applied as well to other portions of the vehicle or to other types of devices to be raised.

The lower portion 16 of the casting 12 serves as a housing for the actuating clamp 17 and the 10 holding clamp 18. The actuating clamp, as best shown in Figure 2, normally loosely embraces the standard 11 and is held in its uppermost position by means of a coiled tension spring 19 which is connected at its ends to lugs 20 formed on the 15 upper surface of the actuating clamp and which passes over a hook 21 formed in the barrel 22 of the casting 12. The spring normally maintains the actuating clamp with its lug 23 in engagement with the housing 12 and with its oppositely disposed portion 24 in engagement with the inner end of the operating lever 25 which is pivoted at 26 to the housing 12. As the operating lever is actuated, as shown in Figure 5, the actuating clamp is tilted slightly upon the standard shaft 25 20 to bring its edge portions 28 and 29 into frictional biting engagement with the shaft. The actuating clamp thus becomes locked upon shaft 11 and continued movement of the operating lever 25 produces a lifting of the entire casting 12. 30 Upon return movement of the operating lever to the position shown in Figure 2, the actuating clamp is returned to normal position by means of the spring 19. It will be noted that the actuating clamp is somewhat S-shaped in cross section as seen in Figures 1, 2 and 5 to bring its engaging edges 28 and 29 toward a common horizontal plane whereby to facilitate the clamping action which these edges may make upon the standard shaft. 35

The casting 12 is held in the position to which it has been raised by means of the holding clamp 18 which, as best seen in Figure 3, embraces the standard shaft below the actuating clamp and has its fulcrum portion 31 projecting through an opening 32 provided in the casting 12. A compression spring 33 is nested within an opening formed in the oppositely disposed end 34 of the holding clamp and bears against the bottom of the casting 12. Normally the compression spring 50 retains the gripping edges 36 and 37 of the holding clamp in continuous engagement with the standard shaft to prevent any retrograde or downward movement of the lifting casting 12 along the shaft. It will be noted particularly, by 55

reference to Figure 3, that the holding clamp is also somewhat S-shaped in longitudinal cross-section to bring the gripping edges 36 and 37 toward a common horizontal plane to facilitate their gripping action upon the shaft. The action of spring 33 combines with any downward force produced upon the portion 31 of the holding clamp by the casting 12 to tilt the clamp upon the shaft and hold the biting edges 36 and 37 in tight engagement therewith to prevent downward displacement of the casting. At the same time the spring permits free upward movement of the holding clamp with the casting 12 so that the clamp is free to travel upward with the casting as the latter is lifted by means of the actuating clamp and the operating lever 25.

The holding clamp may be conveniently released by the insertion of a release lever 39 between the extending portion 34 of the clamp 20 and a depending projection 40 formed on the casting 12. As the outer end 41 of the release lever is moved downwardly as indicated in Figure 1, the portion 34 of the clamp will be cammed downwardly against the action of spring 33 to 25 release the gripping edges of the clamp from the shaft 11. As the clamp is released and the casting 12 moves downwardly, under the weight of the load carried, the inner end 42 of the release lever moves downwardly therewith and thus tends 30 to assume its original relation with respect to the outer end 41 of the lever. By this means the camming action upon portion 34 of the clamp is relieved, and the clamp again grips the shaft under the action of compression spring 33. By 35 this means the downward movement of the lifting casting is under accurate control at all times as the casting will only move downwardly as fast as the outer end of the release lever is moved.

In operation after the base 10 has been 40 ranged upon a suitable support, the casting 12 may be lifted bodily and rapidly along the standard 11 to bring the contact portion 13 thereof into engagement with the load to be raised. This free upward movement of the casting is permitted by both the actuating and holding clamps. The casting may be readily rotated 45 upon the shaft to any desired position to facilitate proper engagement with the load. After the lifting casting has been thus positioned, the operating lever 25 may be operated to further raise the casting and lift the load. The lever may be moved through large arcs of movement to raise the casting 12 a substantial increment upon 50 each operation, or the operating lever may be moved through smaller arcs of movement. This permits operation under conditions wherein the range of travel of the operating lever may be limited by reason of some immovable obstruction. As the lifting casting is raised, it is held against 55 retrograde downward movement by the holding clamp until such time as the release lever 41 is applied, whereupon the downward movement of the casting will be permitted under accurate control.

In the past appreciable difficulty has been 60 encountered with lifting jacks of the friction grip type in securing movement over a sufficient range of lifting travel. By means of the present invention wherein the lifting casting itself carries the 65 gripping clamps and is movable along a standard shaft which may be made as long as desired, this difficulty is overcome. The provision of the springs 19 and 33 for the actuating and holding clamps insures that the operations of these members will at all times be positive and reliable,

and as to the latter precludes any possibility that it may not immediately grip the shaft, thus preventing any possibility of inadvertent release of the jack.

It is obvious that various modifications may be made in the specific embodiment of the invention shown for the purpose of illustration. Accordingly the invention is not to be limited to the precise construction shown and described, but only as indicated in the following claims. 10

The invention is hereby claimed as follows:

1. In a lifting jack, a base, a load actuating member, and means connecting said member and said base for lifting the member from said base, said means comprising a shaft, a friction clamp 15 adapted to engage the shaft, an operating member for tilting the clamp into gripping engagement with the shaft, and spring means for returning the clamp to normal untilted position 20 and into contact with the load actuating member.

2. In a lifting jack, a base, a load actuating member, and means connecting said member and said base for lifting the member from the base, said means comprising a shaft, a friction clamp 25 encircling the shaft and adapted to be tilted into gripping engagement therewith, said friction clamp being adapted to engage the load actuating member and having means thereon which positions it in normal untilted position when in engagement with the load actuating member, and an operating member for tilting the clamp into gripping engagement with the shaft. 30

3. In a lifting jack, a base, an upstanding shaft 35 operatively carried by the base, a load lifting member, means for frictionally gripping the member to the shaft, said means comprising a pair of friction gripping devices, one of which forms a part of means to move the member along the shaft and the other of which is adapted to hold the member against retrograde movement upon the shaft, means for actuating the moving device through variable increments of movement, a spring for urging the holding device to holding 40 position, and means for overcoming the action of the spring to release said holding device, said last named means comprising a laterally extending projection on the holding device and a co-operating abutment means on the load lifting member, said projection and abutment means being arranged in operative juxtaposition on the same side of the load lifting member to receive an operating bar therebetween. 45

4. A lifting jack comprising a base, an upstanding shaft operatively carried by the base, a lifting housing having a load engaging member adapted for movement along the shaft, said shaft being adapted to pass completely through said lifting housing, an actuating clamp within said 50 housing adapted to frictionally embrace the shaft, means comprising a lever pivoted to the lifting housing for moving the actuating clamp relative to the housing while in frictional engagement with the shaft, means causing the actuating 55 clamp to reside in normal untilted position in engagement with positioning means within the housing, a holding clamp also mounted within the housing and adapted to frictionally embrace the shaft, a spring for normally urging the holding clamp into clamping position, and means for releasing the holding clamp from holding position. 70

5. A lifting jack comprising a base, a relatively smooth upright shaft operatively carried by the 75

base, an elongated load lifting member having a load supporting portion at the upper end thereof, said load supporting portion being arranged a substantial distance above the central portion of the load lifting member and comprising an extension substantially embracing the shaft, said shaft being adapted to pass completely through and extend substantially above said load lifting member, a friction clamp adapted to engage the shaft, said clamp being retained normally against positioning means associated with the load lifting member in non-tilted position, and an operating member for tilting the clamp into gripping engagement with the shaft, said load supporting portion being movable to a position below or above the end of the shaft.

6. In a lifting jack, a base, a load actuating member, means connecting said member and said base for lifting the member from the base, said means comprising a shaft, a friction clamp encircling the shaft and adapted to be tilted into gripping engagement therewith, said friction clamp being adapted to be brought into engagement with the load actuating member, means normally positioning the clamp in untilted position when in engagement with the load actuating member, and an operating member pivotally mounted with respect to the load actuating member and having a portion adapted to engage the friction collar clamp for tilting the clamp into gripping engagement with the shaft and for lifting said pivot and said actuating member bodily from the friction clamp as a fulcrum when the clamp is tilted into said shaft gripping engagement.

7. A lifting jack as defined in claim 1, wherein the operating member for tilting the clamp into gripping engagement with the shaft comprises a lever pivotally mounted on the load actuating member and engageable with the clamp.

8. In a lifting jack, a base, a load actuating member, and means connecting said member and said base for lifting the member from the base, said means comprising a shaft, a first friction

clamp adapted to engage the shaft, an operating member pivotally carried by the load actuating member for tilting said clamp into gripping engagement with the shaft, spring means for returning the clamp to normal untilted position and into contact with positioning means associated with the load actuated member, a second clamp, and spring means engageable with said second clamp for tilting it into gripping engagement with the shaft.

9. In a lifting jack, a base, an upstanding shaft operatively carried by the base, a load actuating device longitudinally slidable on the shaft comprising a load engaging member and a housing assembly, and means for moving the load actuating device along the shaft relative to the base comprising a first friction clamp adapted to engage the shaft, an operating lever pivotally mounted on the housing assembly and engageable with the clamp for tilting it into gripping engagement with the shaft, spring means for returning the clamp to untilted position and into contact with positioning means associated with the housing assembly, a second clamp adapted to engage the shaft, spring means for tilting said second clamp into gripping engagement with the shaft, and means for releasing the action of said last named spring means.

10. A lifting jack as defined in claim 9, wherein the load actuating device is of elongated construction longitudinally of the shaft and wherein in the load engaging member constitutes a laterally extending automobile bumper contacting means arranged adjacent the upper end of the load actuating device.

11. A lifting jack as defined in claim 3, wherein the means for actuating the moving device through variable increments of movement comprises a lever pivotally mounted on the load lifting member and engageable with the moving device, and a spring engageable with the load lifting member and also engageable with the moving device for controlling its movements.
